United States Patent Office

Des. 222,515

Patented Oct. 26, 1971

222,515

FOOD PREPARATION COUNTER

George R. Goetz, Bloomington, Minn., assignor to American Dairy Queen Corporation

Filed Mar. 3, 1970, Ser. No. 21,712

Term of patent 14 years

Int. Cl. D7—02

U.S. Cl. D81—10

FIG. 1.

FIG. 2.

Des. 222,515

PAGE 2

FIG. 1 is a perspective view of my food preparation counter;
FIG. 2 is an end elevation view thereof;
FIG. 3 is a front elevational view thereof;
FIG. 4 is a top plan thereof; and
FIG. 5 is a cross sectional view taken on lines 5—5 of FIG. 3.

I claim:

The ornamental design for a food preparation counter, as shown.
